UNITED STATES PATENT OFFICE.

HANS PRYM, OF STOLBERG, GERMANY.

WIRE-Straightening Machine.

Application filed June 2, 1926, Serial No. 113,215, and in Germany May 30, 1925.

This invention relates to a wire straightening machine with a rotating wire straightening spindle, and consists in that the spindle is also moved forward and backward, thereby straightening the wire coming from the wire drawing machines during the forward as well as the backward movement of the straightening spindle. The wire is freed from the twist and at the same time straightened and can at once be worked up.

A construction of a device according to the invention is illustrated in the accompanying drawing, in which Fig. 1 shows the device partly in longitudinal section and partly in front elevation,

Fig. 2 is a plan, and

Figure 3 is a side elevation viewed from the right side.

20 The usual straightening spindle *a* carries in its enlarged part *b*¹ five adjustable straightening pins *b* for the straightening of the wire *q*. The spindle *a* is mounted in ball-bearings *a*¹ within a pipe-like case *c* disposed in a case *d* and fastened therein by the cover *e*. The end of the driving shaft *f* is also mounted in the case *d* and transfers its rotation to the straightening spindle by medium of the toothed wheels *g*, *h*, *i*, and *k*. The shaft *f* furthermore carries a cam disk *l* bordering a roll *m* of a double-armed lever *n* adjustably mounted on a pivot *n*¹. The free end of the lever *n* is forked as at *n*² and engages a box *o* connected by a ball-bearing *o*¹ with the straightening spindle *a*. The box *o* is slideable on rails *p* located beneath the box *o*.

40 A double-armed lever *r* rotatable about *r*² is swung in the known manner by a cam disk *r*¹ and carries at its free end a device *r*³ to feed and draw forward the wire *q*.

The machine works as follows:

45 The straightening spindle *a* is rotated by the shaft *f* by means of the pinion *k* and the toothed wheels *g*, *h*, and *i*, and at the same time moved forward and backward by the lever *n*, guided with its roll *m* in the cam disk *l* and engaging with the other end *n*² with the box *o*. This automatic forward and backward movement of the straightening spindle *a* when passing wire *q* in the direction indicated by the arrows in Figs. 1 and 2 through the straightening pins *b*

removes the twist of the unstraightened wire. The lever *r* drawing the wire step-by-step is moved forward together with the forward movement of the lever *n*, thereby facilitating the passing of the wire through the straightening pins *b*. When the lever *n* and the straightening spindle *a* are moving backward, the feeding lever *r* first stops and holds the wire *q* with the clamping device *r*³. Therefore the wire *q* is freed from the twist on a length dependent from the swinging of the lever *n*. The straightening spindle *a* has 5000 revolutions and the lever *n* makes 550 oscillations per minute; and the extent of swinging of the lever *n* can be varied respectively adapted to the length of the wire to be fed by varying the turning-point *n*¹ of the lever *n*.

I claim:

1. In a wire straightening machine, a rotating spindle carrying straightening means, a double-armed lever for positively reciprocating said straightening spindle in opposite directions, and means to feed the wire during the forward movement of said spindle.

2. In a wire straightening machine, a driven shaft, a cam disk on said shaft, an adjustable lever engaging with said cam disk at one end, a rotating straightening spindle, means to connect the rotating spindle with the other end of the lever, and means to feed wire during the forward movement of said straightening spindle.

3. In a wire straightening machine, a driven shaft, a cam disk on said shaft, an adjustable lever engaging with said cam disk at one end, a rotating straightening spindle, means to connect the rotating spindle with the other end of the lever, another cam disk on said shaft, and wire pulling means controlled by said cam disk.

4. In a wire straightening machine, a rotating spindle carrying straightening means, means to positively move the spindle forward and backward, means to feed the wire during the forward movement of the spindle, and wire pulling means operating in timed relation with the reciprocation of the spindle.

In testimony whereof I affix my signature,

HANS PRYM,
